COKE OVEN

Application filed May 13, 1926. Serial No. 108,751.

This invention relates to high temperature heat transfer structures, and more particularly to heating flues, recuperators, and regenerators, adapted to transfer heat in a by-product coke oven.

The object of the invention is to increase the heat transferring efficiency of hot gases partly by causing a concentration of heat transfer at those surfaces through which the product coke oven.

5 heat is to be transferred, and in part to accentuate this concentration, by constructing the heat transferring surfaces of special material which, it has been discovered, possesses the properties of resistance against physical de-

10 struction under given operating conditions and at the same time preserves to a high degree the property of high heat conductivity.

A major constituent of the operating costs of a by-product coke oven is the cost of the 15 heat required for the carbonization of coal to coke. This heat is usually supplied by burning a fuel in the presence of pre-heated air in heating flues contiguous to the coking chambers. The customary fuel used is a gaseous one, such as producer gas, water gas, blast furnace gas, coke oven gas, and the like. 20 It is the usual practice to preheat the low B. t. u. gas in regenerators or recuperators as well as the air required for the combustion. 25 The pre-heated air and fuel gas meet and burn in the heating flues, as noted heretofore. These burning gases flow through the heating flues and transmit their heat to walls of the latter. The heat then flows 30 through the walls proper to the charge of coal in the coking chambers. The material usually used for the construction of these flues contains silica and is not a rapid conductor of heat. Consequently, with the silica 35 material an excessive high and wasteful temperature must be maintained in the heating flues in order to attain an efficient carbonizing temperature in the coking chambers. In other words, the heat generated in the flues 40 to coke a charge of coal in the coking chamber must be greatly in excess of that theoretically needed, since the low heat-conductivity of the wall between the heating flue and the coking chamber interposes a resistance which 45 must be constantly overcome in order that

the requisite degree of heat actually reaches the coal. In order, therefore, to maintain in the flues a temperature necessary for the coking operation in the coking chamber, excessive quantities of fuel must be burned. 55 Moreover, walls constructed of silica brick, spawl and crack at oven temperatures, thus necessitating constant and expensive repairs and renewals.

A substantial saving in the heat required 60 for carbonization could be effected by constructing the heat transferring wall of material having a high coefficient of heat conductivity, but heretofore it has been believed, upon the basis of numerous experiments, that 65 no material possessing the property of high heat conductivity was sufficiently durable, physically, to withstand disintegration under 70 the prevailing operating conditions. I have, for example, myself endeavored to use 75 material such as well known carborundum refractories, but found that as a general rule such refractories failed to function satisfactorily, especially in that they failed to withstand conditions such as are prevalent in a coke oven flue. I have now found, however, 80 that a refractory wall, when made of shapes or bricks of special refractory material composed chiefly of a component possessing high heat conductivity but containing also an adequate amount of a component which though of less heat conductivity supplies the required cohesive strength will function successfully under conditions prevalent in the heating flues such as those of a by-product coke oven. 85 It is preferable to have the highly conductive component present in the refractory in amounts such that the high heat transmitting qualities thereof is imparted to the refractory as a whole. A typical proportion of components is approximately 90% of carborundum (silicon carbide) and approximately 10% of a highly refractory bonding material such as refractory clay. The proportion of carborundum cannot be increased very substantially over 90% without destroying the capacity of the bricks to withstand the effects of the operating conditions, and the proportion of the bonding component must never be reduced to such a degree that the resulting re- 95 100

fractory fails physically and structurally under actual conditions of operation. I prefer to use a maximum quantity of the highly conductive component and a minimum quantity of the bonding and strengthening component. The percentage of the latter component, although it may be increased, is preferably as low as possible within the limits of the required strength and bonding necessities of the refractory under particular circumstances. In other words, what I require is a silicon carbide brick of high physical strength under the heat conditions prevailing in by-product coke oven practice. A commercial embodiment of the refractory material heretofore described is typified by the carborundum refractory known as carbofrax B disclosed in the patent to Tone, No. 1,204,211 of November 7, 1916. Carbofrax B, contrary to the experience with other refractories of a similar nature, is sufficiently durable to withstand disintegration, while at the same time possessing to a high degree, the desired property of high heat conductivity. In carbofrax B I have therefore discovered a material which by reason of its constituents possesses a high coefficient of heat conductivity, while at the same time the material is extremely resistant against disintegrating effects under the prevailing operating conditions. In fact, a wall of carbofrax B is much stronger at oven temperatures than a wall of silica brick, and does not shrink or expand as much as a wall made of the latter material. It is this new and unexpected property of the carbofrax B material which thus makes it peculiarly adaptable for the purposes of use as the heat transferring wall of a coke oven flue.

In a flue provided with a heat-transferring wall of carbofrax B material, it will be apparent that the non-heat-transferring walls of the flue, when composed of material of a lower coefficient of heat conductivity, will result in a concentration of heat transfer at that part of the flue which is specially intended for the transfer of heat, and that the transfer of heat consequently, through the high heat conductive section of the flue, is intensified and accentuated. This concentration of efficiency may be intensified by partially or entirely lining or enclosing the heat transfer structure with a special heat-insulating material having a lower coefficient of heat conductivity than the customary silica brick. Such an insulating lining or shell will prevent heat losses through the division walls, roof, foundation, and other parts of the coke oven. By isolating each heat transfer unit, the heat is concentrated, thus facilitating the transmission of heat from the heating fluid to the body to be treated. The special material which I have found suitable for use as the heat insulating material, is zirconia. The combination, therefore, of carbofrax B

as the material constituting the heat transferring surfaces and of zirconia as the material constituting the heat insulating surface, is extremely useful for high temperature structures such as coke ovens, particularly in that the coefficients of expansion of these two materials are approximately alike. The relation between zirconia and carbofrax B with reference to their respective coefficients of expansion is of marked importance, for it is this property which makes the conjoint use of these two materials peculiarly and specially appropriate for the special conditions prevalent in coke oven practice.

The tendency in the structure toward cracking and rupturing, due to temperature changes, is therefore greatly reduced, while the efficiency of each part, especially in conjunction with or in relation to the other parts of the structure is materially enhanced.

My invention is applicable, not only to the heating flues of by-product coke ovens, but also to the heat economizing systems of such ovens as exemplified in their usual recuperators or regenerators, as well as to other types of high temperature heat transfer apparatus.

The invention is illustratively exemplified in the structures illustrated in the accompanying drawings, in which Fig. 1 is a sectional view of a part of a by-product coke oven including the coking chamber and heating flues in which my invention is incorporated. Fig. 2 is similar to Fig. 1 of a modified form of my invention. Fig. 3 is a sectional view of a part of a recuperator system embodying my invention. Fig. 4 is a sectional view of a regenerator of a by-product coke oven embodying my invention.

Similar characters of reference designate similar parts throughout the accompanying drawings.

Referring now more particularly to Figs. 1 and 2 of the drawings, the numeral 1 designates a coking chamber of a by-product coke oven having heating flues 2 of the horizontal type and division walls 3 adjacent thereto, all other parts of the oven being omitted for the purpose of clarity. These ovens, generally speaking, are composed of a series of parallel coking chambers similar to chamber 1, having heating flues interposed between adjacent chambers in coke ovens of the vertical flue type, and heating flues adjacent to each side of each coking chamber in ovens of the horizontal flue type. The heating flues may be of any type, but are usually either of the horizontal or the vertical type. In many ovens, particularly those with horizontal flues, division walls of heavy masonry construction are built between contiguous coking chambers, thus isolating each chamber with its heating flues. Associated with the flues are heat economizers or interchangers which function in a well-known manner and usually consist of either regenerators or recuperators.

According to the present invention, the inner walls C of the heating flues 2 contiguous to the interior of the coking chamber 1 are preferably made of carbofrax B. The thermal head or gradient through carbofrax B is approximately but one-fifth of that through the conventional-silica material.

In the preferred embodiment of my invention the outer walls R of the heating flues 2 are made of a refractory material having a very low coefficient of heat conductively, preferably zirconia. Zirconia and the like are heat insulators which transmit heat very slowly, and thus prevent the loss of heat from the heating flues. In some cases it is advantageous to encase not only the outer walls of the heating flues, but also the exposed portions of the coking chamber in a shell of insulating material R as shown in Fig. 2. By this arrangement the coking chamber and related flues are isolated so that the heat from the heating fluid is concentrated in the chambers and is thus utilized with substantially no loss.

In the operation of a by-product coke oven embodying my invention, the chambers 1 are charged with coal in the usual manner. Fuel gas is burned in the heating flues 2 to supply the heat necessary to carbonize the coal to coke. Due to the fact that only a small thermal head or gradient is required to force the heat through my improved lining of the heating flues, a temperature very much lower than that employed heretofore in the heating flues may be used. Since the upper temperature limit is lower, the amount of heat required is greatly reduced, and thus the saving in the number of B. t. u.'s generated to coke a ton of coal is considerable. When my insulating lining or shell is used in conjunction with my conducting lining, an additional saving in heat, and thus in fuel, is obtained. The insulating shell prevents the heat from flowing or leaking into the division walls 3 or into the roof, masonry or foundation of the coke ovens, all indicated as B in the drawings. By this arrangement the heat losses usually occurring in a by-product coke oven from radiation, convection, and conduction, are reduced to a minimum.

A by-product coke oven embodying my invention offers great flexibility in operation, so that any desired type of coke or set of by-products may be obtained according to the mode of operation. By utilizing the same amount of heat per ton of charge which is now being used, I am able to reduce the coking time substantially, thus materially reducing the fixed charges per unit of output and increasing the capacity of the equipment. For example, in an illustrative instance, the coking time is reduced from twelve to eight hours, thus increasing the daily capacity of the equipment fifty percent. On the other hand, when the same period of time as now

used for coking a charge of coal is employed, the quantity of heat required to coke a ton of coal is reduced substantially. As an illustrative example, the heat required may be reduced from 2,100,000 B. t. u. per ton of coal to 1,500,000 B. t. u. per ton of coal, thereby making a reduction of 600,000 B. t. u. per ton of coal.

My invention may also be used to advantage in heat interchangers, such as recuperators, or regenerators. In Fig. 3 I have illustrated a recuperator having my improved linings embodied therein. The letter B designates the masonry which surrounds a recuperator herein shown as one of the channel type, although my invention is adaptable to tubular recuperators and the like. The recuperator illustrated consists of two small channels A and a large channel H interposed between the two aforesaid channels. The large channel is for the hot waste gases coming from the heating flues of an oven and going to the waste stack, whereas the two small channels are for cold incoming air from the atmosphere going to the heating flues. The separating walls C, interposed between the air channels or passages and the hot waste gas channel or passage, are composed of carbofrax B. Surrounding the said passages is a shell R composed of insulating material, preferably zirconia. By this construction the transmission of heat from the hot waste gas to the cold incoming air is facilitated, whereas the flow of leakage of heat to the surrounding masonry is prevented. The air is thus pre-heated to a higher temperature than formerly, and, consequently, higher temperatures may be attained in the heating flues. At the same time the temperature of the waste gas is reduced, so that the thermal efficiency of the ovens is increased.

In Fig. 4, a regenerator is shown embodying my invention. The regenerator is built of checkerbricks C in the usual manner. These checkerbricks are composed of carbofrax B. It is advantageous to encase the highly conductive checkerbrick structure in a shell R of zirconia insulating material so that substantially all of the heat is retained within the checkerbrick and practically none of the heat is permitted to escape. In the operation of a by-product coke-oven the hot waste gas from the heating flue or flues surrounds the checkerbrick on its way to the chimney. As the gas passes through the spaces between the checkerbrick, it gives up its heat to the latter. By making the checkerbrick of material of high heat conductivity, all the heat that is practical to withdraw from the hot waste gas is withdrawn. Upon the reversal of flow of gas, cold air passes in contact with the hot checkerbricks which give up their heat quickly to the air. The transfer of heat is so perfect that substantially all of the heat of the checkerbricks is transferred

to the air, thus raising the temperature thereof to a high value. Moreover, since my improved regenerator possesses a high rate of heat transfer, it may be constructed smaller than the customary type of regenerator, thereby effecting a substantial saving in the initial capital cost of the structure. The increased rate of operation increases the number of reversals of the gas flow per hour.

10 Various modifications may be made without departing from the spirit and scope of my invention as defined in the appended claims.

I claim:

- 15 1. In a by-product coke oven, a coking chamber and heating flues, a part of the walls of each of the heating flues being adjacent to the coking chamber, the walls adjacent to the coking chamber comprising a high heat-transmitting material consisting of approximately 90% silicon carbide and approximately 10% of a refractory bonding material, and the opposite walls of said heating flues comprising a heat insulating material consisting substantially of zirconia.
- 20 2. A by-product coke oven comprising coking chambers and heating walls therefor arranged side by side in alternate relation, said heating walls comprising combustion flues, a part of the walls of each of which are disposed adjacent the coking chambers the walls of said flues disposed adjacent the coking chambers comprising material having substantially all the properties of a refractory
- 25 35 material consisting of approximately 90% silicon carbide and 10% refractory bonding material, and the remaining walls of said flues comprising material having substantially all of the properties of zirconia.
- 40 3. In a coke oven, the combination with a coking chamber, of heating flues, a part of the walls of each of which are adjacent to opposite sides of said chamber, the walls of said flues adjacent to said chamber comprising approximately 90% silicon carbide and 10% of refractory bonding material, and an insulating shell of material having substantially all of the properties of zirconia surrounding said chamber and the walls of said flues opposite to the first mentioned walls.
- 45 4. In a high heat-transfer apparatus, heating flues, a part of the walls of each of which are adapted to transmit heat and the remaining walls of which are insulated against the passage of heat, the heat-transmitting walls comprising high heat-transmitting material consisting of approximately 90% silicon carbide and approximately 10% of a refractory bonding material, and the insulating walls comprising zirconia.
- 50 5. In a by-product coke oven, a coking chamber and heating flues, part of the walls of each of the heating flues being adjacent to the coking chamber, the walls adjacent to the coking chamber comprising a material

having a high heat conductivity and physical strength and the opposite walls of said heating flues comprising zirconia.

6. In a coke oven, a coking chamber and heating flues, part of the walls of each of the heating flues being adjacent to the coking chamber, the flue walls opposite to the walls adjacent to the coking chamber comprising heat insulating material comprising zirconia and the flue walls adjacent to the coking chamber being comprised substantially throughout of a carborundum material having a high heat conductivity.

7. In a coke oven, a coking chamber and heating flues, part of the walls of each of the heating flues being adjacent to the coking chamber, the flue walls remote from the coking chamber comprising a heat insulating material consisting substantially of zirconia, while the flue walls adjacent to the coking chamber comprise material consisting of approximately 90% silicon carbide and approximately 10% of a refractory bonding material and having a high heat conductivity and physical strength and having a coefficient of expansion approximately equal to that of zirconia.

8. A by-product coke oven having heating passages for the hot gases, said passages comprising heat transferring elements composed of approximately 90% of silicon carbide and approximately 10% of fire clay and having a coefficient of expansion approximating that of zirconia.

9. In a coke oven of the type set forth in claim 5 in which the zirconia material forms a continuous protective envelope about said heating flues and coking chamber.

10. In a by-product coke oven, a coking chamber and heating flues, part of the walls of each of the heating flues being adjacent to the coking chamber, the walls adjacent to the coking chamber comprising material containing approximately 90% silicon carbide and approximately 10% fire clay, and having a coefficient of expansion approximating that of zirconia, and the remaining walls of said heating flues being comprised of zirconia.

11. In a by-product coke oven, a coking chamber and heating flues, a part of the walls of each of the heating flues being adjacent to the coking chamber, the walls adjacent to the coking chamber comprising a high heat-transmitting material consisting of approximately 90% silicon carbide and approximately 10% of a refractory bonding material and the opposite walls of said heating flues being comprised of a heat insulating material.

12. A coke oven, having heating flues which have high heat-transmitting portions comprised of a refractory material consisting of approximately 90% silicon carbide and approximately 10% of a refractory bonding material.

13. A by-product coke oven having a coking chamber and heating flues, part of the walls of each of the heating flues being adjacent the coking chamber and said walls adjacent to the coking chamber comprising a high heat-transmitting material consisting of approximately 90% silicon carbide and approximately 10% of a refractory bonding material.
- 10 14. In a high temperature heat-transfer structure, the combination of an insulating shell composed substantially of zirconia, means defining a passage within the shell for a heating fluid positioned to form an adjacent space for receiving heat from said passage, the walls of said passage adjacent said space being composed of high heat-transmitting material consisting of approximately 90% silicon carbide and approximately 10% of refractory bonding material.
- 15 15. In a coke oven, a coking chamber and adjacent heating flues, the flue wall on the side next to the coking chamber space being composed of carborundum brick of substantially the same coefficient of expansion as zirconia and the opposite wall of the flue being composed of zirconia brick.
- 20 In testimony whereof I have hereunto set my hand.
- 25

CHARLES H. HUGHES.
